UNITED STATES PATENT OFFICE

HANS I. HOHLT, OF SANTO DOMINGO, DOMINICAN REPUBLIC

STREAM MOTOR

Application filed April 11, 1928. Serial No. 269,047.

This invention relates to stream motors operative with wind, water, steam, or the like as motive power.

One object of this invention is to provide an improved stream motor which operates in an efficient manner regardless of the direction of flow of the motivating stream, as long as the direction is at an angle to the axis of the motor.

10 Another object of this invention is to provide an improved stream rotor in which the vanes move with their trailing edges foremost.

Another object of the invention is the provision of a device of the character described, wherein the rotor comprises a plurality of vanes equally spaced and symmetrically arranged about the rotor axis, which vanes are stationary throughout the cycle of the motor,

20 and are related in proximity to one another at a particular angle so that a suction may be created upon the exterior face of a vane and a pressure upon the interior face of an adjacent vane, for which purpose the spaces between the vanes freely communicate within the rotor.

A further object of the invention is to produce an improved device of the type specified, in which the vanes are of uniform surface 30 formation and relation to one another for stream line action.

Still another object of the invention is to furnish a device of the nature set forth in which the rotor vanes are angularly disposed 35 to the axis of the rotor for reducing the impact and loss of energy of the motivating stream in its action on the rotor.

Still a further object of the invention is to create an improved device of the species mentioned, which is adapted to operate as a steam 40 turbine.

Other objects will in part be evident and in part pointed out hereinafter.

Generally described, the invention provides a stream rotor which includes a plurality of vanes arranged in stationary relation and in proximity to one another, the spaces between the vanes communicating freely, and the vanes forming such an angle of approach 45 with one another and the motivating stream

that the latter, from whatever direction it may happen to come, will create a reduced pressure on the outside surfaces of certain vanes, and an increased pressure on the inside surfaces of vanes adjacent to those aforementioned, causing the rotor to turn with the vanes moving in the direction of their trailing edges. There may be upper and lower vanes arranged at an angle to one another so that the rotor has a central stream parting 55 action while the vanes recede toward the ends of the rotor in the direction of flow of the stream. The several vanes are in all cases of even surface character so that the eddying of the stream may be reduced. No deflector is employed herein, although the vanes may be rigid on the rotor, since the angle of approach referred to, combined with the spacing of the vanes, makes the same unnecessary.

The rotor includes a main base supporting 60 the vanes at the angle of parting mentioned, the said base being at right angles to the rotor axis and being preferably solid.

Where the device is utilized as a steam turbine, an improved speed control may consist 65 in the use of a plurality of turbine rotors, certain of which are opposed in direction to others thereof.

In the drawings, in which like reference characters designate the same parts in the several views:

Figure 1 is an elevation of an embodiment of the invention.

Fig. 2 is a top plan view of the same with parts broken away.

Fig. 3 is a diagrammatic view illustrating the action and direction of rotation of a rotor vane.

Fig. 4 is a sectional elevation of a modification of the invention, used as a turbine.

Figs. 5 and 6 are similar views of modifications in which a plurality of units are used that may rotate in opposite directions for speed regulation.

The construction herein described constitutes an improvement over my application for patent, Serial No. 124,118, filed October 7th, 1926.

Referring in detail to the drawing, 10 denotes a stream motor embodying the inven-

tion. The said motor includes a rotor 11 that is mounted upon a vertical axial shaft

12. The latter is journaled at its lower free end in a bearing 13 of an anchor plate 14, from which extends upwardly a bracket 15 forming another bearing 16 for the said shaft. Between the said bearings is a bevel gear 17 on the shaft 12, and meshing with the teeth thereof is another bevel gear 18 on a horizontal drive shaft 19 that is journaled in bearing 20 in the bracket 15. A ball bearing support to carry the weight of the rotor 11 is provided at 21 at the bearing 16.

15 While the rotor shaft 12 is supported at only one end thereof, steadiness in a high degree is obtained, since as the speed of the rotor 11 increases, so does the stability thereof, according to the principle of the gyroscope.

20 The rotor includes a plurality of vanes 22 that are in proximity to one another. Each vane has an outer or leading edge 23 and an inner or trailing edge 24. Both the leading and trailing edges of each vane are free so that clear spaces 25 are provided between adjacent vanes. These spaces communicate with the air chamber C within the rotor 11.

25 Each vane 22 forms an angle A with a radial line from the axis of the rotor, which angle is hereinafter designated as the angle of approach of the stream to the vane nearest thereto in the direction of flow. This angle may be approximately thirty degrees. It will be noted that the inside and outside surfaces of each vane are in parallelism. Now, as the motivating stream strikes the rotor 11, a suction or region of reduced pressure is created on the outside of certain vanes and a region of increased pressure or velocity acting against the corresponding vanes is created on the inside thereof. This causes the rotor to turn, and the direction of rotation of the same is dependent solely on the direction of the vanes. More specifically, as shown in

40 Fig. 3, vanes 22 and 26 are shown in diagrammatic relation to each other. In each case the direction of the wind is the same, being indicated by arrow a, yet vane 22 will move clockwise, while vane 26 will move counterclockwise. The action of the currents is as follows: The current, after striking vane 22 is deflected as shown by arrow b, creating a suction on the vane in a clockwise direction. Other current entering space 25, or being deflected thereinto from a next adjoining vane

45 22, strikes the inner side of said vane as indicated by arrows c producing a clockwise force that is additive to that indicated at b. At vane 26 these forces are in opposite direction.

50 The vanes 22 form angles B of approximately forty five degrees with the rotor axis, measuring from the edges of the vanes. Thus the tendency toward a stream line effect is accentuated, and eddying considerably re-

duced, so that the operating efficiency of the device is high.

55 Preferably a main base is provided at 27 which is formed with a plurality of equally spaced, symmetrical points, 28, each of which forms an angle of sixty degrees, as may be readily understood. This base is located centrally between the upper and lower ends of the rotor, and is at right angles to the shaft 12. The vanes 22 are fastened to similar sides of the points 28, and if the rotor is to turn in opposite direction, the vanes are fastened to the opposite sides of said points. The base 27 is solid and acts beneficially in the rotor chamber C as a stream guide. Other bases, or partitions parallel to 27 may be provided.

60 Each vane 22 tapers towards its end at the end of the rotor 11. This taper decreases the working face of the vane nearest the rotor axis, where the stream is least effective. An easy attachment of the vanes is thereby insured, this occurring in any suitable manner, by means of hollow spiders at the rotor ends, or being directly bracketed to the shaft 12.

65 It has been found to be most advantageous that the number of vanes employed be six or multiples of six. The adjacent vanes must be in comparative proximity to one another. If the upper and lower vanes be regarded as separate, then the unit number of vanes 90 might be properly designated as six pairs.

70 While the vanes are here shown as being rigid, they may be pivoted for movement so that the direction of rotation may be reversed or the speed of the rotor reduced for a given velocity of the motivating stream. Other constructions for speed and direction control are hereinafter described.

75 The vanes 22 may be made of any suitable material, as, for example, sheet metal which 105 has the desired weather proof qualities, and its mode of fastening may be any that is well known in the art.

80 In Fig. 4 is shown a modification of the invention, wherein my improved rotor is utilized in a spherical casing 29 so as to provide a steam turbine. The said casing has bearings 30 for the horizontal shaft 31 of the rotor 11. A pair of diametrically opposite openings 32 and 33, whose axes lie in the central transverse plane of the rotor, are provided. The opening 32 constitutes an intake nozzle, while 115 33 is an exhaust outlet. The relation in size of these openings may of course be such as to permit of proper expansion of the steam.

85 In Fig. 5 is shown a further modification of the invention in which a plurality of turbine units are employed, more particularly three in number. Of these the end turbine units 34 have rotors for turning in one direction, while the intermediate unit 35 has its rotors 11^a reversed. Similarly, the direction of flow of steam through unit 35 is opposite to that in units 34. The several rotors are all mounted on one continuous shaft 31^a, and 120

the casings may be interconnected at the bearings 30^a. In operation, units 34 alone are operated, unless it be desired to slow down the shaft 31^a, in which case unit 35 is operated to create a counterforce. To reverse the direction of rotation of the said shaft, units 34 may be idle, and unit 35 operated alone. This arrangement provides a simplified speed and direction control of a high degree of simplicity.

10 By the arrangement shown in Fig. 6, a plurality of intermediate units 35 are provided, so that the force of units 34 may be balanced and the shaft brought to a stop.

15 Further, the shaft may rotate with equal power in either direction, according as the intermediate or end units are operated. A more sensitive speed control is thus ensured.

It will be noted that the speed of any one 20 unit can be directly regulated, as, for example, by throttling the steam supply. Where a plurality of units are employed, automatic control can be provided, so that in the event that the speed of the shaft becomes 25 excessive, steam may be supplied to the intermediate units in a regulated quantity to reduce the shaft speed to a desired number of rotations per minute.

I claim:

30 1. A stream motor comprising a rotor having a plurality of vanes equally spaced about the axis of the rotor in proximity to one another, said vanes being relatively stationary with respect to one another, the spaces between the vanes being in free communication with one another interiorly of the rotor, the said vanes making equal similar angles with the radial lines thereto, so that a region of reduced pressure is created exteriorly of certain of the vanes, and a region of increased 35 pressure interiorly of the said certain vanes, due to the flow of a stream thereagainst, and power transmission means driven by the rotor, said rotor having its maximum circumference intermediate of the ends of the 40 rotor, said vanes sloping from said circumference to the ends of the rotor, said rotor having a partition extending therethrough at said circumference.

45 2. A stream motor comprising a rotor and power transmission means driven thereby, said rotor having a plurality of vanes about the axis thereof, said rotor having a chamber therein between the vanes, the spaces between the vanes freely communicating with said chamber, said vanes making equal similar angles with radial lines of the rotor at an angle to the axis thereof, so that a stream, due to the angle aforesaid, creates regions of 50 reduced pressure exteriorly of the vanes nearest in the line of flow and increased pressure interiorly of the vanes last referred to, causing the vanes to move with their trailing edges foremost, said rotor having its maximum circumference intermediate of the ends

of the rotor, said vanes sloping from said circumference to the ends of the rotor, said rotor having a partition extending therethrough at said circumference.

In testimony whereof I affix my signature. 70
